US0D1071150S

(12) **United States Design Patent** (10) **Patent No.:** **US D1,071,150 S**
(45) **Date of Patent:** **** Apr. 15, 2025**

(54) **I.V. CATHETER**

- (71) Applicant: **MedSource International, LLC**, Chanhassen, MN (US)
- (72) Inventors: **Rachel Ann Sender**, Eden Prairie, MN (US); **Neeraj Gupta**, Gurgaon (IN); **Calvin Todd Fagley**, Excelsior, MN (US)
- (73) Assignee: **MedSource International, LLC**, Chanhassen, MN (US)
- (**) Term: **15 Years**
- (21) Appl. No.: **29/868,934**
- (22) Filed: **Dec. 16, 2022**
- (51) LOC (15) Cl. **24-02**
- (52) U.S. Cl. USPC **D24/112; D24/130**
- (58) **Field of Classification Search**
USPC D24/112-114, 108, 133, 127-130, 186, D24/157
CPC A61M 25/0606; A61M 25/0693; A61M 25/0643

(57) **CLAIM**

The ornamental design for an I.V. catheter, as shown and described.

DESCRIPTION

FIG. 1 is a perspective view of a first embodiment of an I.V. catheter showing our new design;
FIG. 2 is a left side plan view thereof;
FIG. 3 is a right side plan view thereof;
FIG. 4 is a top plan view thereof;
FIG. 5 is a bottom plan view thereof;
FIG. 6 is a front plan view thereof;
FIG. 7 is a rear plan view thereof;
FIG. 8 is a perspective view of a second embodiment of an I.V. catheter showing our new design;
FIG. 9 is a left side plan view thereof;
FIG. 10 is a right side plan view thereof;
FIG. 11 is a top plan view thereof;
FIG. 12 is a bottom plan view thereof;
FIG. 13 is a front plan view thereof; and,
FIG. 14 is a rear plan view thereof.

The broken lines in the figures represent portions of the I.V. catheter which are not part of the claimed design.

1 Claim, 8 Drawing Sheets
